CLAIM

The ornamental design for a showcase, as shown and described.

DESCRIPTION

FIG. 1 is a front, right, top perspective view of the showcase showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is an enlarged detail view taken from the encircled area 8 in FIG. 1.

The broken lines depict portions of the showcase that form no part of the claimed design.

1 Claim, 8 Drawing Sheets
